GUIDE FRAME FOR SHAKER CHUTES

Donald U. Rich, Teaneck, N. J., assignor to
American Car and Foundry Company, New
York, N. Y., a corporation of New Jersey

Application July 23, 1932. Serial No. 624,186

6 Claims. (Cl. 198—220)

This invention relates to reciprocating conveyors known in the art as shaker chutes and has particular reference to a guide frame therefor.

Shaker chutes as used in mining operations and for various other purposes usually comprise a unit composed of a series of metal trough sections connected end to end and suitably supported at intervals by ball frames so as to be capable of reciprocation by a power device. The power device may be of any preferred or desired character and in the present instance is adapted to be connected to one of the trough sections, termed the drive section.

During reciprocation forces arise which tend to shift the unit both vertically and sidewise and it is necessary to provide means to prevent excessive sidewise and vertical shifting of the unit.

The present invention contemplates a new and improved guide frame for shaker chutes which is adapted not only to support the drive trough section in such a manner as to permit reciprocation thereof but is adapted to prevent excessive vertical and sidewise shifting.

Another object of this invention is the provision of a new and improved shaker chute including a drive trough section and a guide frame for supporting the opposite end portions thereof in such a manner as to prevent excessive vertical and sidewise shifting of said trough section.

Another object of this invention is the provision of a guide frame for shaker chutes which is simple and inexpensive to manufacture and strong and durable in operation; said guide frame being so formed as to permit easy and quick replacement of parts should occasion arise.

Other objects and advantages of this invention will be apparent from the following description taken in conjunction with the accompanying drawings in which:

40 Figure 1 is a top plan view of one form of guide frame of the present invention.

Fig. 2 is a sectional view on the line 2—2, Fig. 1; the view showing a trough section attached thereto.

45 Fig. 3 is a broken side elevation of a trough section showing it attached to one of the guide frames illustrated in Figs. 1 and 2; certain portions of the construction in Fig. 3 being indicated in section.

50 Fig. 4 is a sectional view of a modified form of guide frame showing, in section, a trough unit associated therewith.

Fig. 5 is an enlarged side elevation detail view of the construction shown in Fig. 4, certain parts

being broken away to disclose other parts in section.

Fig. 6 is a broken side elevation of a drive trough section showing the guide frame of Figs. 4 and 5 applied to one end portion thereof.

Fig. 7 is a fragmentary detail view, in section, showing a modification of the construction shown in Fig. 4.

Fig. 8 is a fragmentary side elevation of the form of the invention illustrated in Fig. 7, and

Fig. 9 is a fragmentary detail view, in section, showing still another modification of the invention.

Referring now more particularly to the drawings in which similar characters of reference designate similar parts in the several views, the construction shown in Figs. 1-3 inclusive comprises a base frame indicated generally at A which is adapted to support a trough section indicated generally at B; the trough section being of the form shown in section in Fig. 2 though this is merely by way of example. Trough section B is open ended and is provided with a bottom 2 and sides 4 and to said sides, adjacent the end portions of the trough section B, loops 6 are secured adapted to receive suitable connecting elements (not shown) whereby trough sections may be connected to the opposite end portions of the trough section B.

Extending longitudinally of the trough section B and secured to and depending from the bottom 2 thereof is an angle member 8 provided with apertures 10 in the depending leg thereof adapted to receive a connecting bar of a power device (not shown) whereby to reciprocate or shake the trough section B. As clearly shown in Fig. 3, the angle member 8 is arranged intermediate the end portions of the trough section B.

The trough section B is supported for reciprocation by guide frames arranged adjacent the end portions of the trough (see Fig. 3) and in Figs. 1-3 inclusive the guide frame comprises the beforementioned base frame A which is formed of a pair of downwardly facing channels 11 arranged in spaced relation (see Fig. 1). Extending between the channels 11 at points removed from the end portions thereof is a pair of spaced channel members 12 the flanges 14 of which face toward each other as shown clearly in Fig. 2.

The channels 12 are preferably braced by means of angles 15 secured as by rivets 16 to the channels 11 and the webs 17 of channels 12.

The channels 12 serve as a means for guiding the trough section B in the direction of reciproca-

tion as will be more clearly pointed out herein-after and are provided with a pair of oppositely arranged brackets 18 secured to the inner surfaces of the webs 17 thereof by suitable means such as the rivets 20, said brackets constituting bearing means for antifriction elements in the form of supporting rollers 22 mounted on shafts 24 which, in the instance shown, project through the webs 17 of the channels and have securing nuts 26 on said projecting ends. The description pertains specifically to the construction illustrated in Fig. 2 and shows one form of roller which may be mounted on suitable roller bearings. Obviously within the scope of the present invention the rollers may be mounted on shafts which merely project from or are formed with the brackets 18 so that no portion thereof projects through the webs 17 of the channels. The rollers 22 support the trough section for reciprocation, the latter having a pair of spaced angles 30 depending from the lower surface of the bottom 2 arranged to provide a recess therebetween into which a guide frame trough supporting member C in the form of a channel 32 extends. The trough section is connected to the channel member 32 by means of suitable fasteners such as the bolts 34 which extend through the contiguous flanges of the angles 30 and channel 32, as clearly shown in Figs. 1 and 2.

The flanges 36 of the channel member 32 are removed adjacent the end portions of the channel and the web 38 of the channel has its opposite ends upwardly offset as at 40 to provide projecting portions extending under the upper flanges 14 of channels 12 and under wear plates 42 secured as by rivets 43 to the under surfaces of the upper flanges 14 of said channels 12; the wear plates 42 being formed of hardened steel or other suitable material possessing high wear resisting properties. As clearly shown in Fig. 2, the outer edge portions of the wear plates 42 project outwardly beyond the edge portions of the upper flanges 12 of the channels whereby to be in a position such as to contact with wear plates 44 secured to the upper surfaces of the projecting opposite portions of the web 38 of the channel 32; the wear plates 44 being preferably secured by suitable fasteners such as the rivets 46 which also serve to secure angle members 48 to the under surface of the offset end portions of the channel 32 (see Fig. 2); the angles 48 having their vertical legs 50 depending adjacent the end portions of the flanges 36 and channel 32 and said vertical legs 50 are connected to the flanges 36 in any suitable manner as by being welded thereto, as shown at 52. The angle members 48, as clearly shown in Fig. 2, are arranged in such a position as to rest upon the rollers 22 and to reciprocate thereon upon reciprocation of the trough section B through the medium of the power device hereinbefore mentioned.

It will be apparent to those skilled in the art that during reciprocation the trough section B is guided in the direction of reciprocation and that excessive sidewise shifting of the trough section relative to the base frame A is prevented by contact of the wear resisting plates 42 and 44 respectively. It will also be apparent to those skilled in the art that excessive vertical shifting of the trough section and the channel member 32 with its associated angles 48 is prevented by contact of the projecting portions 40 of the web 38 of the channel 32 with the wear resisting plates 42; the construction described being obviously simple and inexpensive to manufacture and pro-

viding a construction in which free and easy reciprocation is effected.

In the construction shown in Figs. 4, 5 and 6 the projecting portions 40 of the channel 32 underlie the upper flanges 14 of the channels 12 and are adapted to cooperate directly with the upper flanges 14 to prevent excessive vertical shifting of the trough section relative to the base frame A. Obviously, if desired, a wear plate may be provided on the under surfaces of the upper flanges 14 of channels 12 in a manner similar to the construction illustrated more clearly in Fig. 2. In the construction shown in Figs. 4-6 inclusive, however, excessive sidewise shifting of the drive trough section B is prevented by cooperating elements connected respectively with the base frame A and the trough section B and in this instance, a restrainer 54 is fitted between the flanges 36 of the channel 32 and is preferably welded as at 56 to said flanges and to the web 38 of the channel and depends below the lower edge portions of the flanges between the upwardly arranged flanges 58 of angle members 60 secured as by rivets 62 to the channels 11 of the base frame. Obviously with the construction just described excessive sidewise shifting of the trough section B relative to the base frame A is prevented by the interengagement of the element 54 with the guideway formed by the spaced angles 60.

In Figs. 7 and 8 a modification of the construction illustrated in the remainder of the drawings is shown in that the base frame includes a channel member 64 arranged parallel with the channel member 11 but interposed substantially midway therebetween and serving to support bearing members 66 which are substantially U-shaped (see Fig. 7) having one leg 68 thereof secured to the web of a Z-section 70 which extends between and connects the pair of channels 11 and the channel 64; the upper flanges 72 of the oppositely arranged Z-sections 70 being inwardly extended and being underlapped by the projecting portions 40 of the channel members 32. For supporting the trough section rollers 74 are journaled on pins 76 supported by the spaced arms 120 of the bearing members 66 and may have one end extended through the webs of the Z-sections 70 to receive a cotter 78 or other suitable securing element.

In Fig. 9, a roller is indicated at 80 and is supported on a spindle 82 journaled in the spaced vertical arms 84 of a U-shaped bearing bracket 86 in the form of a casting provided with oppositely arranged attaching flanges 88 which fit the flanges 90 of channel 64 and are secured thereto by suitable fasteners 92. In this construction the spindle 82 need not project through the web of the Z-section 70 unless such a construction is desired but may be provided with a head 94 countersunk, as shown clearly in Fig. 9, and restrained against accidental displacement by the web of the Z-section. In this construction it will be obvious that should occasion demand, the fasteners 92 may be removed thereby permitting the removal of the bracket 86 from the channel 64.

Figs. 2 and 4 clearly disclose the guide frame of the present invention as including channel members forming guideways or parts of said guide frame, while Figs. 7, 8 and 9 show constructions in which the guide members are formed of Z-shaped metal sections; in Figs. 7, 8 and 9 the rollers are journaled in a bracket secured either to the guide member or to a channel member which connects the guide members. The con-

struction shown in the drawings is susceptible of several modifications within the scope of the appended claims, among which is that in which the bracket members 66 or 86 in Figs. 7 and 9 respectively may be secured to and supported by the lower flanges of the channel members such as disclosed in Figs. 2 and 4, thereby eliminating the necessity of using the intermediate channel 64 shown in Figs. 7, 8 and 9 and providing a construction in which the roller supporting member may be easily and quickly removed from the guide member should occasion demand.

From the above description it is believed that the construction and operation of the guide frame of the present invention will be fully apparent to those skilled in the art. Obviously excessive vertical shifting of the trough section relative to the base frame is eliminated either by contact of the projecting portions 40 of the channel 32 with the wear plates 42 or by direct contact of the projecting portions 40 and the upper flanges 14 of the channels 12 or the upper flanges 72 of the Z-sections 70. Sidewise shifting of the trough section B relative to the base frame is reduced to a minimum in the construction illustrated in Figs. 1-3 inclusive by contact of the wear plates 42 and 44, which wear plates also serve as a means for guiding the trough section in the direction of reciprocation. In the instance shown in Figs. 4-8 inclusive excessive sidewise shifting of the trough section is eliminated by the co-operating members 56 and 60.

The drawings herein illustrate several embodiments of the invention but it is to be understood that these drawings are for illustrative purposes only and various changes in the form and proportions of the device may be made within the scope of the appended claims without departing from the spirit of the invention.

What is claimed is:

1. In a guide frame for shaker chutes, a base frame including channel shaped guide members, rollers adjacent the guide members, a trough supporting member mounted for reciprocation on said rollers and having its end portions lapping the guide members in such a manner as to prevent excessive vertical shifting of the trough supporting member, and cooperating means on the trough supporting member and base frame respectively for preventing excessive sidewise shifting of said trough supporting member.

2. In a guide frame for shaker chutes, guide members, rollers adjacent the guide members, a trough supporting member mounted for reciprocation on the said rollers, and means on said guide members and trough supporting member

adapted to cooperate to guide the trough supporting member in the direction of reciprocation and to restrain said trough supporting member against excessive sidewise shifting.

3. In a guide frame for shaker chutes, a base frame having guide members provided with flange portions, stationary rollers adjacent the guide members, a trough supporting member mounted on the rollers and having portions lapping the flange portions of the guide members in such a manner as to prevent excessive vertical shifting of said trough supporting member, and co-operating elements on the trough supporting member and base frame for preventing excessive sidewise shifting of the trough supporting member.

4. In a guide frame for shaker chutes, a base frame comprising spaced rigid members and guide members connecting the rigid members, a trough supporting body member, tracks at the end portions of said body member, oppositely arranged bearing members mounted on and secured to one of said rigid members and having rollers journaled therein upon which said tracks are supported, said body member and guide members being arranged in overlapping relation whereby excessive vertical shifting of the body member relative to the base frame is prevented, and co-operating means on said body member and rigid members of the base frame for preventing excessive sidewise shifting of the body member relative to the base frame.

5. In a guide frame for shaker chutes, spaced inwardly facing channel members, wear plates secured to the under surfaces of the upper flanges of said members, rollers journaled in said channel members, a trough supporting body member having its end portions arranged in said channel members and provided with wear plates secured thereto so arranged as to contact with said first-named wear plates upon excessive sidewise shifting of said body member, and angle shaped tracks secured to the end portions of said body member and mounted on said rollers.

6. In a guide frame for shaker chutes, a base frame including channel shaped guide members, rollers adjacent the guide members, a trough supporting member mounted for reciprocation on said rollers and having its end portions lapping the guide members in such a manner as to prevent excessive vertical shifting of the trough supporting member, and cooperating means for preventing excessive sidewise shifting of said trough supporting member.
